205,433

MASTER CONTROL UNIT FOR AUTOMATIC LAWN SPRINKLING SYSTEMS

George E. Sanner, Cypress Hill, Sparks, Md.

Filed May 18, 1965, Ser. No. 85,344

Term of patent 14 years

(Cl. D91—1)

Fig. 1

FIGURE 1 is a side view of a master control unit for automatic lawn sprinkling systems embodying my new design; and

FIGURE 2 is a perspective view of the master control unit of FIGURE 1 with a removable cover separated from the remainder of the unit.

The pipe shown in broken lines is included for illustrative purposes only.

I claim:

The ornamental design for a master control unit for automatic lawn sprinkling systems, substantially as shown and described.
